(57) **CLAIM**

The ornamental design for a food container housing food articles, as shown and described.

DESCRIPTION

FIG. 1 is a perspective view of a food container housing food articles showing my design;

FIG. 2 is a side elevation view thereof;

FIG. 3 is a top plan view thereof; and,

FIG. 4 is a bottom plan view thereof.

The broken line portion of the figure drawings is included to show unclaimed subject matter only and forms no part of the claimed design.
